Attorney

UNITED STATES PATENT OFFICE.

FRANK ALEXANDER, OF ROCHESTER, INDIANA.

CUE-TIP DRIER.

Application filed May 10, 1927. Serial No. 190,230.

My present invention has to do with the drying of tips on billiard cues; and it contemplates the provision of a simple and easily used device through the medium of which tips may be dried and set on billiard and other cues adequately and in a very short period of time, and this with little or no effort on the part of the user of the device and in such manner that the cues are out of the way while the drying process is proceeding, and the cues are not subject to be affected by atmospheric conditions which frequently, when the cue is set in the atmosphere, delay and interfere with the drying of a newly applied tip on the cue.

To the attainment of the foregoing the invention consists in the improvement as hereinafter described and definitely claimed.

In the accompanying drawing, forming part of this specification:—

Figure 1 is a front elevation of the cue tip drier constituting the preferred embodiment of my invention.

Figure 2 is a vertical section of the same taken at right angles to Figure 1.

Figures 3 and 4 are detail views herein-after explicitly referred to, Figure 4 being a horizontal section taken on the plane indicated by the line 4—4 of Figure 2 looking downwardly.

Similar numerals of reference designate corresponding parts in all the views of the drawing.

Among other elements, my novel device comprises a bracket 1 fixed to a wall or other support designated by 2.

The bracket 1 is provided in its upper side with a plurality of pockets 3, preferably arranged in circular series as illustrated, and designed to receive and seat and hold the heel ends of cues such as shown by dotted lines in Figure 2 and designated by 4.

Arranged an appropriate distance above the bracket 1 is the oven 5 of my novel drying device. The said oven 5 is preferably, though not necessarily, of sheet metal, and is provided in its lower wall with apertures 6 for the reception and passage of cues, the said apertures 6 being preferably arranged in a circular series and with the apertures in coincidence with the before mentioned pockets 3 in the bracket 1.

Within the purview of my invention, the oven 5 may be maintained in any appropriate

manner in spaced relation above the bracket 1. I prefer, however, to interpose between and connect with the bracket 1 and the oven 5 a vertical central rod-like support 7, and I also prefer to interpose between and connect to the bracket 1 and the oven 5 upright supports such as 8, the latter being arranged at diametrically opposite points and preferably at or adjacent to the perimeters of the bracket 1 and the oven 5. From this it follows that the bracket 1 and the oven 5 will be maintained in fixed relation to a wall or other upright support such as 2. In this connection I would have it understood that a body may be employed at the point 2 to carry the bracket 1 and the oven 5, and the said body 2 may be screwed or otherwise fastened to a wall or other appropriate support in a pool or billiard room or other apartment in a building. In this connection it will be noticed that an upper bracket 9 is interposed between and connected to the body 2 and the rod-like central support 7 with a view to holding the oven 5 against gravitation away from the body 2 or the wall as the case may be.

In the oven 5 and preferably in the center thereof is an incandescent electric lamp 10 which constitutes an efficient heating agent. The said lamp is designed to be connected in conventional manner with an appropriate source of electric current supply.

It will be apparent from the foregoing that cues to which fresh tips have been applied may be expeditiously and easily placed in my novel device in the manner indicated, so that the tip bearing portions of the cues will be within the oven 5 and about the lamp 10. When so disposed, the oven being heated by a lamp of about seventy-five watts, the tips will dry perfectly and without liability of burning in a temperature of about one hundred and twenty degrees F.

It will also be appreciated that the cues may be readily placed in and removed from my novel device, and incident to the drying operation the cues will be held in a space of small compass without liability of any one of the cues being accidentally displaced, and during the drying operation, the tip bearing portions of the cues are not subjected to any change of temperature. Again it will be appreciated that my novel device is adapted to be disposed in a corner or other out of the way place in a room, and that

when properly embellished, my novel device is calculated to constitute an attractive piece of furniture or appurtenance for a billiard or pool parlor.

5 It is well known to operators of billiard and pool parlors that during damp weather, the glue attaching tips to cues becomes damp and tips fly off and in many cases the old tip is damaged, and manifestly when the 10 operator is confronted with the condition indicated, it is feasible for him to apply new tips to the cues and then place the cues in my novel device whereupon in a couple of hours the tips will be perfectly dry and the 15 cues will be ready to put back into commission.

In the preferred illustrative embodiment of my invention, the oven 5 comprises a bottom wall 11 and a hood portion 12, the hood 20 portion 12 carrying the lamp 10 in its top and being hinged at 13 to the bottom wall 11, so that when desired, the hood portion 12 may be swung laterally toward the left in Figure 1 to the position shown in Figure 25 3 so as to afford ready access to the interior of the oven. The flexible connections 14 complementary to the lamp 10 do not interfere in any measure with the hood portion 12 being swung off and on the bottom wall 30 11; and it will be understood that if preferred the tips may be glued to the cues while the upper portions of the cues are placed as shown in Figure 2 and then the hood portion 12 may be swung over the 35 upper end portions of the cues and on the bottom wall 11 so as to confine the heat given off by the lamp 10 in the oven and thereby accelerate the drying the cue tips. It will also be manifest that by virtue of the hinge 40 connection 13 of the hood portion 12 the cue tips may be conveniently inspected at intervals with a view to ascertaining when they are perfectly dry and set.

I have entered into a detailed description 45 of the construction and relative arrangement of the parts embraced in the present and preferred embodiment of my invention in order to impart a full, clear, and exact understanding of the said embodiment.

50 I do not desire, however, to be understood as limiting myself to the precise structure shown and described, my invention being defined by my appended claims within the scope of which modifications may be made 55 without departure from my invention.

Having thus described the invention, what I claim is:—

1. A cue tip drier comprising an upright support, a bracket fixed to said support and having a circular series of pockets in its upper side, an oven spaced above said bracket and including a bottom wall with a circular series of apertures therein fixed to the upright support, and also including a hood hingedly connected to said bottom wall and swingable on and off the same, a support interposed between and connected to the bracket and the bottom wall of the oven, and an incandescent electric lamp carried by the top wall of the hood and adapted when the 60 hood is positioned above the bottom wall of the oven to heat the interior of the oven.

2. A cue tip drier comprising a support for cues, an oven maintained in spaced relation above said support and having apertures in its bottom wall for the reception of cues, and means in the oven for affording heat with a view to drying tips on the cue portions within the oven.

3. A cue tip drier comprising a bracket, 80 an oven supported in spaced relation above said bracket and having apertures in its bottom wall for the reception of the tip bearing portions of cues, and an incandescent electric lamp disposed in the oven and carried by the top wall thereof.

4. A cue tip drier comprising a cue support, and an oven disposed in spaced relation to said support and having a wall with apertures for the passage of the tip bearing portion of cues and also having a hood movable to and from opposed relation to said wall, and an incandescent electric lamp provided with flexible electric connections and carried by the wall of the hood in opposed relation to the said apertured wall and adapted to move with the hood to and from the opposed relation to the apertured wall.

5. An oven for drying cue tips, adapted to be heated, and having an apertured wall for the passage of the tip bearing portions of cues; the said oven having in addition to said apertured wall a hood hingedly connected to the wall, and an incandescent electric lamp carried by and movable with the hood and having a flexible connection to supply current to the lamp.

In testimony whereof I affix my signature.

FRANK ALEXANDER.
